UNITED STATES PATENT OFFICE

134,121

DESIGN FOR A COMBINATION DICKEY BLOUSE

Toby Katzman, New York, N. Y.

Application May 28, 1942, Serial No. 107,039

Term of patent 7 years

To all whom it may concern:

Be it known that I, Toby Katzman, a citizen of the United States of America, residing at New York, county and State of New York, have invented a new, original, and ornamental Design for a Combination Dickey Blouse, of which the following is a specification, reference being made to the accompanying drawing, forming a part thereof.

In the drawing:

Fig. 1 is a front elevational view of a combination dickey blouse showing my design,

Fig. 2 is a rear elevational view of the combination dickey blouse shown in Fig. 1, and

Fig. 3 is a side elevational view thereof.

I claim:

The ornamental design for a combination dickey blouse, substantially as shown.

TOBY KATZMAN.
